UNITED STATES PATENT OFFICE.

JAMES D. SHYER, OF DETROIT, MICHIGAN.

DOOR-BRACE.

1,304,394.

Specification of Letters Patent. Patented May 20, 1919.

Application filed December 6, 1918. Serial No. 265,596.

To all whom it may concern:

Be it known that I, JAMES D. SHYER, a citizen of the United States, residing at Detroit, in the county of Wayne and State 5 of Michigan, have invented new and useful Improvements in Door-Braces, of which the following is a specification.

This invention relates to door securing devices, particularly to that type employed 10 supplementary to the ordinary door lock or other securing means, and has for its object the provision of an adjustable bracing member adapted for engagement upon a door knob upon the inside of a room and 15 having its other end engageable with the floor at a point spaced from the door, the construction and arrangement of this device being such as to prevent opening of the door.

20 An important object is the provision of a device of this character, the floor engaging legs of which are adjustable so that it may be used upon any door provided with a knob regardless of the height of the knob 25 above the floor.

Another object is the provision of a device of this character which is so constructed that a portion thereof will serve to cover the keyhole to prevent spying upon 30 the occupant of the room.

A further object is the provision of a device of this character which will be extremely simple and inexpensive in manufacture, which will be highly efficient and 35 durable in use, which may be readily disassembled for convenience in carrying in a traveling bag and which will be a general improvement in the art.

With the above and other objects and advantages in view, the invention consists in 40 the details of construction to be hereinafter more fully described and claimed and illustrated in the accompanying drawings in which:—

45 Figure 1 is a perspective view of my device applied to a door.

Fig. 2 is a detail view of the upper end of the device showing in details the movable knob engaging member and

50 Fig. 3 is a detail sectional view through one of the legs.

Referring more particularly to the drawings the letter A designates a door from which protrudes the usual knob B. My 55 device is indicated broadly by the letter C and comprises a V-shaped body 5 formed

preferably as a single casting and including divergent tubular leg portions 6 connected at their upper ends by the plate portion 7. Rods 8 are disposed for slideable adjustment 60 within the leg portion 6 and may be held in adjusted positions by means of suitable set screws 9.

At its upper end, the body 5 has formed thereon a plate portion 10 provided at its center with a semi-cylindrical recess 11 and having one end portion provided with a threaded hole 12 and having its other end portion provided with spaced upstanding ears 13. A clamping plate 14 is pivoted 70 between the ears 13 and has its central portion provided with a semi-cylindrical recess 15 complementary to the recess 11. At its free end, the clamping plate 14 is provided with a threaded hole within which is disposed a clamping screw 16 engageable with 75 in the hole 12.

In use, my device is applied to a door by engaging the recess 11 upon the shank of the knob B, after which the clamping plate 80 14 is swung into engagement with the knob shank and the clamping screw 16 threaded into the hole 10. The device being thus firmly attached to the door knob the legs 8 are so adjusted that they will engage the 85 floor at a point spaced from the door, after which the set screws 9 are tightened to hold the legs in adjusted positions. When the rods 8 are adjusted to the proper length, the device will be inclined in respect to the door 90 as clearly shown in Fig. 1. After the brace has been thus applied it will be obvious that any attempt to open the door will be frustrated as even extremely slight inward movement of the door will result in such 95 binding as to make further movement impossible. It will be noted that the plate portion 7 connecting the leg portions 6 will extend over the key hole and serve as a blind for preventing spying upon the occupant of 100 the room. When the use of the device is not required, the rods 8 may be telescoped in the leg portions 6 so that the device will be in compact form convenient for storage in a suit case or other suitable traveling bag.

105 From the foregoing description and a study of the drawing it will be apparent that I have thus provided an extremely simple and efficient device which may be readily engaged upon a door knob and which is so constructed as to prevent any unauthorized opening of the door and which

will be consequently a great protection against the efforts of these and others.

While I have shown and described the preferred embodiment of the invention, it will of course be readily understood that I reserve the right to make such changes in the form, construction and arrangement of parts as will not depart from the spirit of the invention nor the scope of the subjoined claims.

Having thus described my invention I claim:—

1. A device of the character described comprising a V-shaped body including tubular leg portions and a plate connecting said leg portions, rods connected with said leg portions and engageable with a floor, a plate member formed on the upper end of said body and provided with a recess engageable with the shank of a door knob, and a clamping member carried by said second named

plate and adapted for embracing engagement with the shank of the door knob.

2. A device of the character described comprising a V-shaped body including tubular leg portions and a plate connecting said leg portions, rods slidably adjustable within said leg portions and engageable with a floor, a plate member formed on the other end of said body and provided with a recess engageable with the shank of a door knob, a clamping plate hingedly connected at one end upon said second named plate and provided with a recess complementary to said first named recess for embracing engagement upon the shank of the door knob and a clamping screw carried by the other end of said clamping plate and engageable with said second named plate.

In testimony whereof I affix my signature. 40

JAMES D. SHYER.

Copies of this patent may be obtained for five cents each, by addressing the "Commissioner of Patents, Washington, D. C."
